UNITED STATES PATENT OFFICE.

ARTHUR C. DAVIDSON, OF CHICAGO, ILLINOIS, ASSIGNOR, BY MESNE ASSIGNMENTS, TO
WAUGH DRAFT GEAR COMPANY, A CORPORATION OF ILLINOIS.

BUFFING MECHANISM FOR CARS.

1,301,397.

Specification of Letters Patent. Patented Apr. 22, 1919.

Application filed February 27, 1913. Serial No. 750,961.

To all whom it may concern:

Be it known that I, ARTHUR C. DAVIDSON, a citizen of the United States, residing at Chicago, in the county of Cook and State of Illinois, have invented certain new and useful Improvements in Buffing Mechanism for Cars, of which the following is a specification.

This invention relates to strain resisting mechanism for railway cars and the like and has for its object the provision of an improved arrangement for absorbing buffing and other strains and cushioning the cars against violent and injurious shocks. More specifically the invention aims to produce a buffing device wherein in an improved manner a graduated resistance is effected and in which the extent of compression which can be imparted to the spring resistance elements is limited so as to prevent injury thereto from going solid or becoming set. The invention further provides for improved gear supporting and guiding means and gear-retaining means to prevent displacement of the elements while at the same time affording means for their ready assembling. A further object of the invention is the provision of means whereby to increase the angular flexibility of the buffer to maintain the opposed faces of the buffers carried by adjacent cars in contact when rounding sharp curves.

Other objects and advantages of the invention will be apparent from the accompanying drawing and the detailed description based thereon wherein is set forth a preferred embodiment of the invention. Obviously the invention is capable of embodiment in other and varied constructional forms, wherefore the drawing and description is to be construed in an illustrative and not in an unnecessarily limiting sense.

In the drawing:

Figure 1 is a top plan view of a skeleton cast steel platform embodying the invention, certain portions being shown in horizontal section;

Fig. 2 is a vertical longitudinal section taken on the line 2—2 of Fig. 1;

Fig. 3 is a transverse section on the line 3—3 of Fig. 1;

Fig. 4 is a similar section on the line 4—4 of Fig. 1;

Fig. 5 is a fragmentary sectional detail showing the relation of the gear supporting

and guiding members and wear plate in their relation to the spring disks; and

Fig. 6 is a detail perspective view showing one of the members of the interlocking follower;

Fig. 7 is a top plan view of a composite platform frame embodying the invention;

Fig. 8 is a vertical longitudinal section taken on the line 8—8 of Fig. 7;

Fig. 9 is a transverse section on the line 9—9 of Fig. 7; and

Fig. 10 is a similar section on the line 10—10 of Fig. 7 with slight modifications as to details.

In Figs. 1—6 of the drawings the invention is illustrated as embodied in a cast steel platform construction integral with the car underframe end sill and it is in this connection that the invention will be first described, although it is to be understood that the invention is capable of embodiment with the underframe structure of cars having no platforms and with composite or built-up platform frames as distinguished from an integral skeleton structure.

Herein the reference numeral 11 designates the end sill of a cast steel car underframe of the type now in general use, and formed integral with and projecting forwardly therefrom is a skeleton platform frame composed of a series of vertically disposed longitudinally extending web members 12. Spaced apart from and in substantially parallel relation to the end sill, and formed integral with and fixed rigidly to the forward end of said longitudinal web members is a buffer beam 13 of the usual construction. Located upon the central portion of the buffer beam is a threshold plate 14 while in front of the buffer beam 13 is positioned a buffer 15, provided on top with a horizontal plate 16 adapted to slide beneath the threshold plate 14. The buffer 15 is carried by the forward ends of a pair of side buffer stems 17, 17, pivoted to said buffer at 18, 18, and the central portion of the buffer bears against the forward end of a center buffer stem 19, all of these stems being arranged to slide freely through alined openings 20 and 21 formed in the front and rear walls of the buffer beam 13.

In line with the axis of the car and in the space between two adjacent webs 12 which occupy such central position is mounted the buffing gear. These two web members ex-

tend from an integral connection with the end sill at 22 to a substantially integral connection with the buffer beam at 23. Although parallel and practically straight, these members are shown as having a slight offset at 24, 24 which defines the dividing line between the forward portion 12^a and the rear portion 12^b, the former being entirely open and the latter of a solid structure cored 10 out to provide a pair of pockets 25, 25 each adapted to accommodate a pair of coiled concentrically arranged gear springs 26 and 27. The two springs are of dissimilar length and strength, the outer spring 26 being longer and of less resistance than the inner spring 27.

The forward portions 12^a of the web members 12 are provided below with inwardly projecting gear-supporting flanges 28 and 20 upon their inner walls with inwardly projecting gear-guiding or bearing ribs 29, and above for a portion of the length with inwardly projecting gear-retaining flanges 30.

Upon the flanges 28 is supported a rear 25 follower 31 having a concave front face and a flat rear face, the latter bearing against the forward ends of the springs 26. Immediately in front of the follower 31 and bearing against its concave front face and supported 30 by the flanges 28 is a series of flat spring plates 32, and immediately in front of the spring plates 32 is a front follower 33 having a convex rear face bearing against the flat plate springs and provided in its front face 35 with a recess adapted to receive the inner end of the center buffering stem 19.

A wear plate 34 may be advantageously inserted between the spring plates 32 and the supporting flanges 28, and bearing flanges 40 29, the functions of the parts and their operation being the same in either case.

The front follower may also be advantageously formed of interlocking members 35 and 36 in order to facilitate the assembling 45 of the parts of the gear. The follower member 35 is provided in its front face with a recess 37 and on each side thereof with a beveled portion 38, while the follower member 36 which has a width corresponding to 50 the distance between the beveled portions of the member 35 has upon its rear face a projection 39 adapted to enter the recess 37 and upon its front face a recess 40 adapted to receive and accommodate the rear end of the 55 center buffering stem 19.

The gear-retaining flanges 30, it will be observed, extend but a portion of the distance from the cored housing 12^b toward the front end of the open housing 12^a, and immediately 60 in front of the end of the flanges 30 is arranged a gear-retaining cover plate 41 which is removably secured in place by the screws 42.

Extending laterally from and connecting 65 the longitudinal web members 12 are integral

transverse web members 43 and 44. The transverse web members 43 are provided with apertures 45 in longitudinal alignment with the apertures 21 of the buffering beam. Within each of the apertures 45 is mounted a 70 sleeve 46 having at its forward end a flange 47 which bears against the front face of the web 43 while the body of the sleeve itself extends for a considerable distance to the rear of the flange 43. The side stem 17 extends 75 through the sleeve 46 and has threaded upon its rear end a nut 48 which is advantageously fixed in adjusted position by a cotter pin 49, while the coil spring 50 is mounted upon the side stem 17 so as to bear rearwardly upon 80 the flange 47 of the sleeve 46 and forwardly upon the washer 51 which bears in turn toward the front against a shoulder 52 formed on the side stem and also against the rear face of the buffering beam. 85

By the arrangement of the resistance mechanism applied to the center stem and side stems of the buffer the said buffer previous to coupling is maintained under spring pressure in a forward position slightly in advance of the coupling line, this pressure being exerted through the center stem by the initial compression of the springs 26 and through the side stems by the initial compression of the springs 50 bearing to the rear 95 on the flange 47 and to the front on the washer 51 and the shoulder 52. When coupled the buffer is displaced to the rear, the side stem nuts 48 also traveling to the rear away from the sleeve 46, and the followers 100 31 and 33, and plates 32 traveling bodily to the rear upon the supporting flanges 28 and between the bearing ribs 29 until the follower 31 contacts with the springs 27 and places the latter under slight compression. Any 105 subsequent buffering strains serve to move both the side stems and center stem farther to the rear and such additional strains are first absorbed by the resistance of the spring 27 added to that of the spring 26 until the rear 110 face of the follower 31 contacts with the front portion of the cored housing 12^b which arrests its rearward movement and thereafter the buffering strain is sustained by the high resistance plates 32. 115

When rounding short curves the rearward pressure upon that end of the buffer at the inside of the curve pushes its side stem to the rear turning the buffer upon the center stem as a pivot and throwing the opposite end of 120 the buffer farther to the front than its normal position. Under such circumstances the sleeve 46 yields to the forward pull of the nut 48 on the side stem and travels bodily toward the front until the nut itself engages 125 the rear face of the web 43 thus permitting a wide range of angular movement on the part of the buffer.

In assembling the parts of the buffering gear the springs 26 and 27 are first inserted 130

from the front into the pockets 25, the rear follower 31 is dropped into the forward housing through the space to the front of the gear-retaining flanges 30 and moved 5 backward into contact with the springs. The spring plates 32 are then inserted one at a time in a similar manner and then the front follower member 35 is dropped into place. At this time the spring members of 10 the buffing gear are not under compression and the rearmost plates 32 are in a position to the front of the front end of the retaining flange 30. In order to place the springs under initial compression and to force all 15 of the plates 32 far enough to the rear so as to be beneath the retaining flanges 30 suitable wedging devices are employed coating on the one hand with the beveled faces 38 of the follower member 33 and on the other 20 hand with the rear face of the buffer beam whereby to wedge the followers and spring plates to the rear and place the spring 26 under compression. While the wedges remain in position the follower member 36 is 25 dropped into place in front of the follower member 35 and the wedges are then removed permitting the member 35 to spring forward and the projection 39 to enter the recess 37. The center stem 19 then engages within the 30 recess 40 and the interlocked follower members 35 and 36 are positioned against upward displacement. The removable retaining plate 41 is then secured in position and the entire buffing gear is safely housed 35 against displacement.

In that form of the construction shown more in detail in Figs. 7 to 9 inclusive the reference numeral 61 designates the forward portion of the center sills of a car while 62 40 indicates a transverse sill or end sill, as the case may be, forming a part of the car underframe. The buffer beam 63 is mounted on the forward end of the center sills which latter form the longitudinal members of a 45 housing to accommodate therebetween the buffing gear. The composite or built-up structure here shown is essentially the same so far as the present generic invention is concerned as the integral skeleton structure 50 previously shown and described. Upon the inner walls of the center sills 61 are fixedly secured by bolts or rivets 64 a pair of reinforcing web members 65, 65 each of which has upon its lower edge an inwardly projecting integral gear supporting flange 66 and along its upper edge an inwardly projecting gear retaining flange 67, while between its upper and lower edges it is provided with an inwardly projecting bearing 55 or guiding rib 68.

The rear portion of the space within the housing between the webs 65 is, as in the construction previously described, cored out to form pockets for the interior and exterior 60 springs 69 and 70, the front wall 71 of the

pocket structure serving as a rear abutment or stop for the rear follower 72 which bears normally upon the front end of the springs 70. In front of the follower 72 in contact with its concave face and below the retaining flanges 67 is disposed upon the supporting flanges 66 a series of spring plates 73 and in front of the spring plates and bearing thereon is the interlocking follower 74^a. As in the former case the flanges 67 do not 75 extend forwardly above the front follower 74^a but are cut away and their function is performed by a transverse retaining plate 75 secured to the upper edge of the center sills 61 and provided on its lower face with 80 downwardly projecting ribs 76 which bear upon the upper edge of the front follower and the forward members of the spring plates.

Upon the outer faces of the center sills 61 85 are mounted a pair of brackets 77 horizontally apertured to serve as a rear bearing support for side stems 78 which are slidably supported within aligned apertures 79 of the buffer beam 63 and which are pivoted at 80 90 to the buffer 81 which latter rests in its central portion against the front end of the center stem 82 guided within apertures 83 and 84 of the buffer beam with its rear end seated in the recess 85 of the duplex interlocking follower 74^a.

In Fig. 10 I have shown a slight modification in which the webs are integral with the sills and in which the gear retaining flanges instead of being formed integral 100 with the longitudinal webs 65 are formed as separate members 86 and secured to the sills 61 by means of rivets or bolts 87 which also serve together with the bolts 88 to hold the bracket 77 in place. In this form, the 105 gear supporting flanges 89 and the gear guiding ribs 90 are formed integral with the longitudinal sills. I have also in Fig. 10 shown the employment of a wear plate 91 between the lower edges of the spring 110 plates 73 and the supporting flanges 89.

As in the former construction the side stems 78 are equipped with springs 92 which bear forwardly upon washers 93 resting against shoulders on the stems and against 115 the rear face of the buffer beam 63 within recesses 94. Rearwardly the springs 92 bear against the inner flanged end 95 of tubular sleeves or thimbles 96 slidably mounted within the apertures of the brackets 77.

I claim:

1. In a buffing mechanism, the combination of a car underframe, a buffer beam and a pair of longitudinally extending parallel spaced members arranged in fixed relation 125 to said underframe, said members having inwardly projecting gear-supporting flanges and bearing ribs, substantially as described.
2. In a buffing mechanism, the combination of a car underframe, a buffer beam, a 130

pair of longitudinally extending spaced members having fixed relation to the underframe, said members having integral inwardly projecting gear-supporting flanges and bearing ribs, the latter arranged intermediate the top and bottom on the inner faces of said members, substantially as described.

3. In a buffing mechanism, the combination of a car underframe, a buffer beam and a pair of longitudinally extending parallel spaced members arranged in fixed relation to said underframe, said members having inwardly projecting gear-supporting flanges and bearing ribs, and a spring housing between the ends of said members, substantially as described.

4. In a buffing mechanism, the combination of a car underframe, a buffer beam and a pair of longitudinally extending parallel spaced members arranged in fixed relation to said underframe, said members having inwardly projecting gear-supporting flanges and bearing ribs, and a wear plate for the gear bearing on the upper face of the flanges and the inner faces of the ribs, substantially as described.

5. In a buffing mechanism, the combination of a car underframe end sill, a composite frame associated therewith and including a buffer beam and a pair of longitudinally extending spaced web members, said members having along their lower edges inwardly projecting gear-supporting flanges and along their inner faces intermediate the top and bottom thereof gear-bearing ribs, substantially as described.

6. In a buffing mechanism, the combination of a car underframe end sill, a composite frame associated therewith and including a buffer beam and a pair of longitudinally extending spaced web members, said members having along their lower edges integral inwardly projecting gear-supporting flanges and along their inner faces intermediate the top and bottom thereof integral gear-bearing ribs, and a spring housing between the ends of said members, substantially as described.

50 7. In a buffing mechanism, the combination of a car underframe end sill, a composite platform frame associated therewith and including a buffer beam and a pair of longitudinally extending spaced web members, said members having along their lower edges integral inwardly projecting gear-supporting flanges and along their inner faces intermediate the top and bottom thereof integral gear-bearing ribs, and a wear plate for the gear bearing on the upper face of the flanges and the inner faces of the ribs, substantially as described.

8. In a buffing mechanism, the combination of a car underframe, a buffer beam, and a pair of longitudinally extending spaced

web members arranged to the rear of the buffer beam, said members having along their lower edges inwardly projecting gear-supporting flanges, and along their upper edges inwardly projecting gear-retaining flanges, and between their lower and upper edges inwardly projecting bearing ribs, substantially as described.

9. In a buffing mechanism, the combination of a car underframe, a buffer beam, and a pair of longitudinally extending spaced web members arranged to the rear of the buffer beam, said members having along their lower edges in their forward portion integral inwardly projecting gear-supporting flanges and along their upper edges in their medial portion integral inwardly projecting gear-retaining flanges, and along their forward portion between their lower and upper edges inwardly projecting integral bearing ribs, and a removable gear-retaining plate disposed upon the members forward of the gear-retaining flanges, substantially as described.

10. In a buffing mechanism, the combination of a car underframe, a buffer beam, a pair of longitudinally extending spaced web members arranged to the rear of the buffer beam, said members having along their lower edges in their forward portion integral inwardly projecting gear-supporting flanges and along their upper edges in their medial portion integral inwardly projecting gear-retaining flanges, and along their forward portion between their lower and upper edges inwardly projecting integral bearing ribs, and a removable gear-retaining plate disposed upon the members forward of the gear-retaining flanges, and a spring housing integral with and between the rear ends of the members, substantially as described.

11. In a buffing mechanism, the combination of a supporting frame including longitudinal spaced members, brackets projected laterally therefrom, a buffer beam, a buffering gear, a buffer, a center stem connecting the buffer and gear, and side stems connected with the buffer and guided for longitudinal movement in aligned apertures of the beam and brackets, a flanged sleeve mounted on each of the side stems and guided within one of the apertures with its flange bearing upon the front face of the bracket, and a compression spring on the side stem between the flanged sleeve and the rear wall of the beam, substantially as described.

12. In a buffing mechanism, the combination of a supporting frame including longitudinal spaced members, brackets projected laterally therefrom, a buffer beam, a buffering gear, and side stems connected with the buffer and guided for longitudinal movement in aligned apertures of the beam and brackets, a flanged sleeve mounted on the

free end of each of the side stems and guided within the aperture of the bracket with its flange bearing against the forward face of said bracket and its rear end projecting beyond the rear face, and a spring on the side stem between the bracket and beam and bearing to the rear on the flanged sleeve and to the front upon a shoulder of the stem and the rear face of the beam, and a stop on the free end of the stem and bearing on the rear end of the sleeve, substantially as described.

13. In a buffing mechanism, the combination of a supporting frame including longitudinal spaced members, brackets projected laterally therefrom, a buffer beam, a buffing gear, a center stem connecting the buffer and gear, and side stems connected with the buffer and guided for longitudinal movement in alined apertures of the bracket and beam, a flanged sleeve mounted on the free end of each of the side stems and guided within the aperture of the bracket with its flange bearing against the forward face of said bracket and its rear end projecting beyond the rear face, and a spring on the side stem between the bracket and beam and bearing to the rear on the flanged sleeve and to the front upon a shoulder of the stem and the rear face of the beam, and a nut threaded on the free end of the side stem and adapted to engage the rear end of the sleeve, substantially as described.

14. In a buffing mechanism, the combination of a car underframe end sill, a composite platform frame associated therewith and including a buffer beam and longitudinal web members with laterally projecting brackets, buffing mechanism mounted between the longitudinal web members, a buffer, a center stem connected with the gear and the buffer, side stems connected to the buffer and guided within alined apertures of the brackets and beam, a flanged sleeve mounted on the free end of each side stem and guided within the aperture of the rear bracket with its flange bearing on the front face thereof and its rear end extending beyond the rear face, a shoulder formed on the stem, a washer bearing upon the shoulder and upon the rear face of the beam, a spring on the stem and bearing to the rear upon the flange of the sleeve and to the front upon the washer, and a stop carried by the free end of the side stem and adapted to engage the rear edge of the sleeve, substantially as described.

15. In a buffing mechanism, the combination of a car underframe end sill, a platform frame associated therewith and including longitudinal and transverse web members, a pair of the adjacent longitudinal web members having along their lower edges inwardly projecting gear supporting flanges, and upon their inner faces gear-bearing ribs, and a buffing gear mounted within the space be-

tween said longitudinal members upon the supporting flanges and between the bearing ribs, a buffer, a center stem connected with the gear and the buffer, side stems connected to the buffer and guided within alined apertures of the transverse webs, a flanged sleeve mounted on the free end of each side stem and guided within the aperture of the rear transverse web with its flange bearing on the front face thereof and its rear end extending beyond the rear face, a shoulder formed on the stem, a washer bearing upon the shoulder and upon the rear face of the forward web, a spring on the stem and bearing to the rear upon the flange of the sleeve and to the front upon the washer, and a stop carried by the free end of the side stem and adapted to engage the rear edge of the sleeve, substantially as described.

16. In a buffing mechanism, the combination of a car underframe end sill, a platform frame associated therewith and including longitudinal and transverse web members, a pair of the adjacent longitudinal web members having along their lower edges inwardly projecting gear supporting flanges, and upon their inner faces gear-bearing ribs, and along their upper faces inwardly projecting gear-retaining flanges, buffing gear mounted within the space between said longitudinal members beneath the gear-retaining flanges upon the supporting flanges and between the bearing ribs, a buffer, a center stem connected with the gear and the buffer, side stems connected to the buffer and guided within alined apertures of a pair of transverse webs, a flanged sleeve mounted on the free end of each side stem and guided within the aperture of the rear web with its flange bearing on the forward face thereof, a shoulder formed on the side stem, a washer bearing on the shoulder and upon the rear face of the forward transverse member, a spring on the stem and bearing to the rear upon the flange of the sleeve and to the front upon the washer, and a nut on the end of the side stem and adapted to engage the rear end of the sleeve, substantially as described.

17. In a buffing mechanism, the combination of a supporting frame comprising longitudinal members, certain of the members having along their forward lower portion inwardly projecting gear-supporting flanges and along their medial upper portion inwardly projecting gear-retaining flanges, the retaining flanges terminating short of the space between one end of the members, and gear housing between the other ends of the members, coil springs disposed between the members in the housing, a follower and a series of springs resting on the supporting flanges beneath the retaining flanges, and a second follower resting upon the supporting flanges and in advance of the ends of the retaining flanges, a removable retaining

plate overlying the second follower, a buffer, and a buffer stem disposed between the buffer and the second follower, substantially as described.

- 5 18. In a buffing mechanism, the combination of a supporting frame comprising longitudinal members, certain of the longitudinal members having along their forward portion inwardly projecting gear-supporting flanges and along their medial upper portion inwardly projecting gear-retaining flanges, the retaining flanges terminating short of the forward ends of the members, a gear housing between the rear ends of the members, coil springs disposed between the members in the housing, a rear follower, and a series of spring plates resting on the supporting flanges beneath the retaining flanges, and a front follower resting upon the supporting flanges in advance of the ends of the retaining flanges, a removable retaining plate overlying the front follower, a buffer, and a buffer stem disposed between the buffer and the front follower, substantially as described.

- 10 19. In a buffing mechanism, the combination of a supporting frame comprising longitudinal members, certain of the longitudinal members having along their forward portion inwardly projecting gear-supporting flanges and along their medial upper portion inwardly projecting gear-retaining flanges, the retaining flanges terminating short of the forward ends of the members, a gear housing between the rear ends of the members, coil springs disposed between the members in the housing, a rear follower, and a series of spring plates resting on the supporting flanges beneath the retaining flanges, and a front follower resting upon the supporting flanges in advance of the ends of the retaining flanges, a removable retaining plate overlying the front follower, a buffer, and a buffer stem disposed between the buffer and the front follower, the front follower comprising two interlocking members, one follower member provided with means to place the springs under initial tension preparatory to the introduction of the other follower member, substantially as described.

- 15 20. In a buffing mechanism, the combination of a supporting frame comprising longitudinal members, certain of the longitudinal members having along their forward portion inwardly projecting gear-supporting flanges and along their medial upper portion inwardly projecting gear-retaining flanges, the retaining flanges terminating short of the forward ends of the members, a gear housing between the rear ends of the members, coil springs disposed between the members in the housing, a rear follower, and a series of spring plates resting on the supporting flanges beneath the retaining flanges,

and a front follower resting upon the supporting flanges in advance of the ends of the retaining flanges, a removable retaining plate overlying the front follower, a buffer, and a buffer stem disposed between the buffer and the front follower, the front follower comprising two interlocking members, one having a rear bearing face for engagement with the spring plates and a front face provided with a recess and with beveled portions adjacent thereto adapted to be engaged by a wedge member to place the springs under initial tension, and the other follower member having on its rear face a projection for engagement within the recess and on its front face a recess to accommodate the end of the center stem, substantially as described.

21. In a buffing mechanism, the combination of a supporting frame comprising longitudinal and transverse web members, certain of the longitudinal members having along their forward lower portion inwardly projecting gear-supporting flanges and along their medial upper portion inwardly projecting gear-retaining flanges, the retaining flanges terminating short of the forward ends of the members, a gear housing between the rear ends of the members, coil springs disposed between the members in the housing, a rear follower, and a series of spring plates resting on the supporting flanges beneath the retaining flanges, and a front follower resting upon the supporting flanges in advance of the ends of the retaining flanges, a removable retaining plate overlying the front follower, a buffer, and a buffer stem disposed between the buffer and the front follower, side stems connected with the buffer and guided for longitudinal movement in a pair of transverse web members, a flanged sleeve mounted on the free end of each of the side stems and guided within the rear transverse member with its flange bearing on the front face and its rear end extending beyond the rear face thereof, a shoulder on the side stem, a washer bearing on the shoulder and on the rear face of the front transverse web member, a spring on the side stem and bearing rearwardly upon the flange of the sleeve and forwardly upon the washer, and a stop carried by the free end of the side stem and adapted to engage with the rear end of the sleeve, substantially as described.

22. In combination with a car underframe including center sills, transverse sills, and buffer beam of longitudinal reinforcing web members secured to the inner faces of the center sills and having along their lower portion inwardly projecting gear supporting flanges, and a buffing gear housed in the space between the said web members above the supporting flanges, substantially as described.

23. In combination with a car underframe

including center sills, transverse sills, and buffer beam, of longitudinal reinforcing web members secured to the inner faces of the center sills and having along their lower portion inwardly projecting gear supporting flanges, and along their upper portion inwardly projecting gear retaining flanges, and a buffing gear housed within the space between the said members and between the upper and lower flanges, substantially as described.

24. In combination with a car underframe including center sills, transverse sills, and buffer beam, of longitudinal reinforcing web members secured to the inner faces of the center sills and having along their lower portion inwardly projecting gear supporting flanges, along their medial portion inwardly projecting gear guiding ribs, and along their upper portion inwardly projecting gear retaining flanges, and a buffing gear housed within the space between the said members and between the flanges and ribs thereof, substantially as described.

25. In combination with a car underframe including center sills, transverse sills, and buffer beam, of longitudinal reinforcing web members secured to the inner faces of the center sills and having along their lower portion inwardly projecting gear supporting flanges, and along their upper portion inwardly projecting gear retaining flanges, a buffing gear housed within the space between the said members and between the upper and lower flanges, a pair of brackets secured to the outer faces of the center sills at the rear of and substantially in the horizontal plane of the buffer beam, a buffer, a center stem connecting the buffer and gear, and said stems connected with the buffer and guided for longitudinal movement in aligned apertures of the beams and brackets, substantially as described.
